D. A. ADAMS

METHOD FOR FILING AND BINDING DOCUMENTS AND THE LIKE

Filed Sept. 18, 1920

Patented Feb. 20, 1923.

1,446,408

UNITED STATES PATENT OFFICE.

DOUGLAS ALLEN ADAMS, OF DUNEDIN, OTAGO, NEW ZEALAND.

METHOD FOR FILING AND BINDING DOCUMENTS AND THE LIKE.

Application filed September 18, 1920. Serial No. 411,105.

To all whom it may concern:

Be it known that I, DOUGLAS ALLEN ADAMS, a subject of King George V of Great Britain, and resident of 40 Dowling Street, Dunedin, Otago, New Zealand, have invented certain new and useful Improvements in Methods for Filing and Binding Documents and the like, of which the following is a specification.

10 This invention relates to files for keeping together papers, letters and the like documents.

15 The object of the invention is to provide a simple apparatus for the filing of papers, letters and the like.

A further object is to provide a quick, simple and efficient method of binding such documents when they are taken from a file to be placed away for reference.

20 By using my method and apparatus, the purchase and use of numerous files is unnecessary, and at the same time a binding is provided which is practically permanent.

25 While this specification sets forth the present and approved construction of the device, still in practice deviations from such detail may be resorted to as do not depart from the spirit and scope of the invention.

30 In the drawings accompanying this specification,

Figure 1 is a perspective view showing position of inner covers when the file is full and the binding cord or tape in place for starting binding operations.

35 Fig. 2 is a rear perspective view of the file showing the cord drawn through the central hole.

40 Fig. 3 is a rear perspective view of the file showing the loop drawn through the hole threaded in the standards.

45 Fig. 4 is a rear perspective view of the file showing the file withdrawn from the standards and the loops pulled through the holes.

Fig. 5 shows a rear perspective view of the file with the cord completely tied thereon.

Figure 6 is a part sectional view showing binding boards and backing piece partially applied.

50 Figure 7 is an enlarged view of the slotted end of the pillar member.

To one of the covers 1 or back pieces of the file is secured a main plate member 2. Attached to one side of the said plate mem-

ber are two or more vertical solid standard 55 members 3, each free end 4 of which is slotted, as at 4^A and 4^B, forming a connecting channel from without the standard member 3 with the slot 4^A so that a cord 13 may be introduced within the said slot 4^A without 60 being threaded; if desired, the communicating slot may be dispensed with.

The object of having the form of slot in the solid pillar members (clearly shown in Figure 7) is to prevent the binding cord 65 from becoming disengaged when being drawn through a hole in the file to form a loop, and also to prevent the disengagement when the papers are removed from the full file.

70 Constructed preferably from a length of wire of suitable gauge, and opposing the solid standard members, are two pillars 6 and 6^A, having arched tops 6^B, the horizontal portion 6^C of the wire forming the pillars 75 being pivotally retained in members 7 secured to the main plate 2 in a manner to permit movement of the pillars 6 and 6^A to and from the said vertical solid standard members 3, so that their respective ends may 80 engage. Flat spring members 8 are attached to the main plate 2 and serve the purpose of retaining the arched pillar members in a closed or open position, a portion of the horizontal wire 6^C being flattened as at 85 6^D to engage the flat spring 8 when the arched portion 6^B of the pillar members 6 and 6^A engage with the slotted end 4 of the solid standard members 3.

90 There is a hole 9 in the main plate member 2 preferably centrally between the vertical solid standard members; this hole is for the purpose of permitting entry and withdrawal of a detached barbed cord threader 10, the use of which will be herein- 95 after described.

The said detached barbed cord threader 10 consists of a length of wire having one end looped as at 10^A, and the other end in the form of a barb, as at 10^B; this member may 100 be preferably housed in a pocket secured to the cover member 1^A.

105 It will of course be apparent that the letters, papers and the like are punched with holes 12 to register with the solid standard members 3 and the centrally disposed hole 9 in the main plate member 2.

Having described the parts comprising my

file, I will now describe the method adopted to bind the papers, letters and the like when they are taken from a full file.

To bind legal documents or papers of 5 foolscap size or larger, which are used often for reference, and in order to give a strong permanent binding approximately over the whole of the length of the papers, the following method is adopted.

10 Loop cord or tape 13 and pass the barbed cord threader 10 downwardly through the centre hole 12 in the papers, and through the centrally disposed hole 9; engage the loop in the barb of member 10 and withdraw 15 said member and loop, as at Figure 2; draw it well through, spread the loop 13^A to join with the slotted end of each standard member; draw tight the two loose ends 13^B and 13^C of the cord 13 which are placed through 20 the file, then raise the papers from the file; this produces two loops, 13^D and 13^E, one in each slotted end of the standards.

Disengage the loops 13^D and 13^E from the slotted end of the standard members, holding 25 the loops in the hand. Now take the two ends 13^B and 13^C of the cord, and place one end 13^B through one loop 13^D, and one end 13^C through the other loop 13^E; draw the cord tight, take each end, pass it round the 30 back of the bound papers, as at 13^F, pass it under the cord at 13^G, Figure 10. Now take the ends 13^B and 13^C, and pass them round the ends of the document or thread them through a hole or holes 12^A Figure 10, then

through the loops 13^D and 13^E, and tie the 35 ends securely.

The bound papers may be attached to stiff cover members 14 by any suitable means as in the manner of a book, Figure 11, or the binding of the cover members and the papers 40 may be effected simultaneously if desired.

I claim—

A method of binding papers on a file consisting in placing a plurality of sheets 45 formed with openings near the upper edge in superimposed relation upon a pair of standards formed with slotted ends, drawing a loop or cord through an opening in the file between the standards to the front portion 50 of the file, threading portions of said loop in the standards, withdrawing the file from the standards to thread the loop portions through the openings to form two loops at the back of the file, threading each end of the cord through one of the loops after 55 which the ends are passed around the top edge of the file and under the cord at the front of the file, then outwardly toward the edges of the file, then the ends are passed through openings near the outer edge to the 60 back of the file and subsequently each end is passed through and tied to one of the loops.

In witness whereof I affix my signature.

DOUGLAS ALTON ADAMS.

Witnesses:

ROBERT WALES,

ROBERT PARK, Jr.
